UNITED STATES PATENT OFFICE.

ROBERT H. PLASS, OF UPPER MONTCLAIR, NEW JERSEY, ASSIGNOR TO POLORIS COMPANY, INC., OF NEW YORK, N. Y., A CORPORATION OF NEW YORK.

MECHANISM FOR CHARGING PORTABLE RECEPTACLES.

Original application filed February 26, 1926, Serial No. 90,921. Divided and this application filed February 4, 1927. Serial No. 165,864.

This invention relates more especially to packaging machines of the character shown and described in my copending application Serial Number 90,921, filed February 26, 5 1926.

The primary object of my invention is to provide mechanism of improved construction whereby receptacles or cartons may be expeditiously charged from a continuing 10 supply of articles which are to be packaged and distributed.

Another object of my invention is to provide circular-inserting and carton-charging mechanisms of improved construction and 15 arrangement with respect to a conveyor which presents open cartons in successive positions to receive circulars and articles which are being presented in substantially continuous series for this purpose.

20 Specific objects of invention will appear in the specification and be pointed out in the appended claims, reference being had to the accompanying drawings which exemplify my invention in its adaptation to a 25 machine for charging cartons with poultices preparatory to the distribution of said poultices to the trade. Said drawings constitute reproductions of some of the drawings and portions of others as originally filed in 30 my copending application Serial Number 90,921, filed February 26, 1926, the present application being a division of the former case.

In the drawings

35 Figure 1 is a partial top plan view of a packaging machine embodying my improved mechanism for charging portable receptacles.

Figures 2 and 2^a together constitute an 40 enlarged vertical section on the line 2—2^a, Figure 1, parts being shown in elevation.

Figure 3 is a horizontal section on the line 3—3 of Figures 2 and 2^a, portions of the fixed table or top plate being broken away.

45 Figure 4 is an enlarged top plan view of the circular-inserting mechanism shown in Figure 1, parts being broken away.

Figure 5 is a vertical section corresponding to the line 5—5 of Figure 4, parts being 50 shown in elevation.

Figure 6 is a vertical section corresponding to the line 6—6 of Figure 5, parts being broken away and parts shown in elevation.

Figure 7 is a horizontal section corresponding to the line 7—7 of Figure 5, parts being broken away and parts shown in plan. 55

Figure 8 is an enlarged fragmentary section corresponding to the line 8—8 of Figure 5, parts being broken away and with the inner slide shown in a relatively advanced position. 60

Figure 9 is a vertical section on the line 9—9 of Figure 8, parts being shown in elevation. 65

Figure 10 is an enlarged vertical section of the poultice-charging mechanism, parts being broken away and parts shown in elevation.

Figure 11 is a vertical section corresponding to the line 11—11 of Figure 10. 70

Figure 12 is an enlarged fragmentary section corresponding to the line 12—12 of Figure 10.

Figure 13 is an enlarged horizontal section corresponding to the line 13—13 of Figure 10. 75

Figure 14 is a horizontal section corresponding to the line 14—14 of Figures 2 and 2^a. 80

Figure 15 is an enlarged horizontal section corresponding to the line 15—15 of Figure 2.

Figure 16 is an enlarged horizontal section on the line 16—16 of Figures 2 and 2^a. 85

Referring more especially to Figures 1, 2, 2^a, and 3 of the drawings, a lower plate 1 which is carried by uprights 2, is provided with an opening 3 for the accommodation of a bearing 4 carried by an integrally-formed plate 5, said plate 5 being secured to the plate 1 around the edge of opening 3 by means of bolts 6. A power shaft 7 which is journaled in a bearing 8 carried by a pedestal 9 mounted upon the plate 1, has keyed thereto a bevel pinion 10 which meshes with a bevel gear 11 keyed to a vertical cam shaft 12, the lower end of said cam shaft being journaled in the bearing 4. The upper end of the bearing 4 is provided with a thrust bearing plate 13 between which and an upper bearing plate 14 are arranged suitable ball bearings 15. It will be seen from Figure 2 that the bevel gear 11 is provided with a hub 16 by means of which the end-thrust on bevel gear 11 may be taken by the bearing plate 14. The upper end of the cam shaft 12 is journaled in a bearing 17 carried 90

100

105

by an upper plate or table 18 which is mounted upon the uprights 2. Keyed to the upper end of the cam shaft 12, as shown in Figure 3, is a spur gear 19 which meshes with a second spur gear 20 journalled upon a stud 21 threaded into the top plate 18. Threaded into the spur gear 20 near the periphery thereof is a stud 22 on which is pivotally mounted one end of a link 23, the other end 5 of said link being pivotally connected to a stud 24 carried by a lever arm 25 which swings about a stud 26 mounted in the top plate 18. The bifurcated outer end 27 of lever arm 25 engages a roller 28 journalled 10 on a stud 29, said stud being threaded into an inwardly-presented protuberance 30 of an oscillatory ring 31. As shown in Figure 2, the ring 31 rests upon the surface of table 18 and has its outer periphery in slidable 15 contact with the inner base flange of a cylindrical housing 32, said housing being rigidly mounted upon the upper plate or table 18 and constituting a supporting frame 20 for the carton-conveyor which is now to be described. For this purpose, a cylindrical frame 33 which forms a part of the carton-conveyor, is provided with an outwardly-presented flange 34 which is slidably mounted 25 in an inwardly-presented groove in the upper portion of stationary frame 32, said carton conveyor being thereby supported independently of ring 31 so as not to interfere with the latter's reverse movements. Adjacent its lower edge, the traveling frame 33 30 is provided with a plurality of inset dog and ratchet blocks 35 which, as shown clearly in Figures 3 and 10, are provided with upper rectangular recesses 36 and lower acute-angled recesses 37. Each of said rectangular recesses 36 is adapted to receive the squared outer end 38 of a locking dog 39 which, as shown in Figure 3, is pivotally mounted upon a stud 40 and yieldably held 40 in locking engagement with the recess 36 by means of a spring 41. Each of the lower recesses 37 is adapted to receive a ratchet pawl 42 which is pivotally mounted upon a stud 43 carried by the ring 31. Said pawl is pressed outwardly by means of a leaf spring 44 so that during clockwise movements of 45 the drive ring 31, the cylindrical frame or support 33 is made to partake of its movement whereas during the counter-clockwise movements of ring 31, the ratchet pawl 42 will be dragged from the lower recess 37 and after sliding along the inner wall of frame 33, will drop into the next recess 37 in the lower series. At the end of each counter-clockwise movement of the drive ring 31, a pin 46 carried thereby, will be thrown into engagement with an inclined surface 45 near the outer end of locking dog 39, for displacing said dog from rectangular recess 36 and thus releasing the cylindrical support 33 to 50 partake of the next clockwise movement of

the ring 31, which thus imparts a clockwise movement to the carton conveyor. Referring now to Figures 2, 2^a and 10, it will be seen that the traveling frame or support 33 is surmounted by a rigid castellated frame 70 or structure including raised carton-carrying plates or tables 50 which are circumferentially interposed between depressed portions 51 of the structure and integrally connected thereto by spaced uprights 52 (see Figures 75 2, 5 and 10). Presented in opposite directions from the uprights 52 are lugs 53 which carry suitable pivots 54 for carton-gripping levers, each of said levers comprising a gripper-arm 55 provided with an elongated 80 clamping jaw 56 and a lever arm 57 provided with an anti-friction roller 58. These gripping levers are adapted to receive a carton and by means of the step-by-step movements imparted to said carton-conveyor to present 85 said carton in one position after another so that successive operations may be carried on in the manner explained in my above identified copending application. Certain of these operations to which the present application 90 appertains more especially, are carried on by suitable mechanisms which may be described as follows:

Circular-insert mechanism.

Referring to Figure 2^a, a power shaft 177 which is journalled in bearing 178 carried by bracket 179 which depends from the underside of table 18, carries a bevel pinion 180 which meshes with a bevel gear 181, said gear 181 being keyed to the lower end of a vertical shaft 182 indicated in dotted lines in Figure 4. As indicated in dotted lines in said Figure 4, the upper end of shaft 182 has a worm 185 keyed thereto and meshing into a worm gear 186, said worm gear being keyed to a horizontal shaft 187 which is journalled in bearings 188 and 189. A miter gear 190 which is keyed to the other end of shaft 187 meshes into a second miter gear 191 keyed to a shaft 192 which is journalled at opposite ends in bearings 193 and 194. Referring now to Figures 5 and 7, the shaft 192 has keyed thereto a cam 195 over which travels a cam roller 196 journalled upon a stud 197 carried by the strap end 198 of a rod 199 which is pivotally connected at its other end by a pin 200 to an oscillatory crank arm 201 which is pivotally mounted upon a cross-shaft 202. A spring 203 exerts pressure on the lever arm 201 in such a way as to hold the cam roller 196 in contact with the cam 195. A guide block 204 is mounted upon the shaft 192 in slidable engagement 100 with the walls of a longitudinal slot 205 with which the strap 198 is provided for constraining the movements of that end of the rod under the action of cam 195. The upper end of crank arm 201 is provided with a slot 206 within which operates a roller 105 110 115 120 125 130

207 journalled upon a pin 208, said pin being carried by laterally spaced bearing lugs 209 which depend from opposite edges of a channelled slide 210. Said roller 207 is 5 spaced from the bearing lugs 209 by collars 211. Secured to the left end of slide 210, according to Figure 4, is a flattened box-like receptacle 212 which as shown in Figures 8 and 9 is provided at its inner end with a 10 narrow discharge opening 213, said opening being formed by inwardly contracted top and bottom portions of the walls of said receptacle. The lateral dimension of said receptacle is also contracted by an inward displacement of the edge walls 214 of said receptacle to facilitate its introduction into the open end of a carton C presented thereto by the carton-conveyor after one of its 15 periodic movements. As shown in Figure 20 4, the receptacle 212 is provided with laterally presented tabs 215 secured to the forward end of slide 210 by screws 216. The slide 210 is provided with a central longitudinal opening 210^a and is carried by laterally-spaced slides 217 which reciprocate in grooves 217^a in side frames 227. A plate 218 secured to slides 217, forms therewith a guide-way for an inner slide 219. The forward end of slide 219 is provided with 25 projections 220 as shown in Figure 8, said projections being adapted to engage the rear edge of a folded circular S for propelling it thru the outlet 213 of receptacle 212 and for retaining said circular within the carton 30 C during the withdrawal of said receptacle. In order to accommodate the projections 220 and to permit them to project beyond the forward end of the box-like receptacle 212, the inwardly contracted walls of said receptacle, are provided with slots 221, thus permitting the full retraction of the receptacle 35 from the carton before the inner slide 219 is withdrawn therefrom. As shown in Figure 5, the slide 219 is provided on its under side 40 with a rack 222 into which meshes a floating gear pinion 223 carried by a transverse shaft 224 journalled in bearing blocks 225, said blocks being slidable in longitudinal grooves 226 formed in the side frames 227. 45 Interposed between the blocks 225 and anti-friction rollers 228 carried by pin 224 on opposite sides of pinion 223, are spacing collars 229. The rollers 228 operate in slots 230 in the outer ends of laterally-spaced 50 crank arms 231 which project upwardly from an elongated hub 232 journalled upon a cross-shaft 233 mounted in the side frames 227. Keyed to the cross-shaft 192 is a second cam 234 over which runs a cam roller 235 journalled upon a stud 236 projecting from the strap end of a rod 237, said strap end being provided with a longitudinal slot within which is disposed a guide block 238 carried by shaft 192. The forward end of 55 cam rod 237 is pivotally connected to a stud 239 which projects laterally from one of the crank arms 231, the cam roller 235 being retained in running contact with the cam 234 by means of a spring 240 which exerts a pressure on the other crank arm 231 for 70 this purpose. Arranged below the floating pinion 223 and meshing therewith is a fixed rack 241 over which said floating pinion travels with a cycloidal movement which imparts to the slide 219 a movement due to 75 the rotation of said pinion, increased by the distance traveled by the axis of said pinion. The operation of this mechanism may now be readily understood and briefly described 80 as follows:

Suitable mechanism for feeding off circulars from a pile, for folding said circulars, and for feeding the folded circulars to the above-described circular-insert mechanism, 85 is indicated as a whole in Figure 4 by the reference character 250. As here represented, this mechanism constitutes an organization of parts substantially similar to that shown in Figures 1 and 7 of the drawings in U. S. Patent No. 1,605,560 which was granted in my name under date of November 2, 1926.

According to the present application, this mechanism 250 delivers a folded circular to the bottom slide 210 immediately in front of the projections 220 of inner slide 219. The forward movement of slide 210 under the control of cam 195, is accompanied by the more rapid forward movement of slide 219 under the control of cam 234, the net result 95 of these forward movements being to deliver the circular S within carton C in the position shown in Figures 8 and 9. At this time, the retracting movement of receptacle 212 has already begun as indicated by the forms and relative positions of cams 195 and 234 as shown in Figures 5 and 7. During the retracting movement of receptacle 212, the rear edge of the circular C is engaged by projections 220 of slide 219 and hence remains behind within the carton C. The inner slide 219 is then withdrawn from the carton after which the next periodic movement of the table conveys the carton 105 into position to receive the poultices or other articles to be charged therewith.

Poultice charging mechanism.

Referring now to Figures 1 and 2^a, an endless chain conveyor comprising links 260 provided with projecting lugs 261 passes about a polygonal drum 262 carried by a shaft 490 journalled in a bracket 263. Suitable means for driving this endless chain conveyor may be provided as follows. A power shaft 477 which is journalled in bearing brackets 478 and 479, carries a bevel pinion 480. Meshing with the bevel pinion 480 is a bevel gear 481 which is keyed to 115 a short vertical shaft 482 journalled in a

bearing 483 carried by a bracket arm 484 which projects laterally from the bearing bracket 479. Keyed to the upper end of the short vertical shaft 482 is a large spur gear 485, said spur gear being in mesh with a small spur gear 486 (see dotted lines in Figure 2^a), which is keyed to the lower end of a vertical shaft 487. Keyed to the upper end of vertical shaft 487 is a bevel pinion 488 which meshes with bevel gear 489, said bevel gear 489 being keyed to the short horizontal shaft 490 which carries the polygonal drum 262. The lower run of said conveyor travels thru a chute 264 which terminates adjacent to a reciprocable carrier tray or chute 265 said carrier tray being provided with laterally projecting pins 266 which are movably engaged by the bifurcated ends 267 of lever arms 268. Said lever arms are keyed to a rock shaft 269 which is journalled upon a fixed axis in laterally spaced frames. A crank arm 270 which is also keyed to said rock shaft, carries a wrist pin 271 to which is pivotally connected the upper end 272 of a rod 273. Said rod is provided at its lower end with a strap 274 journalled upon a eccentric disk provided with a hub 275 keyed to power-shaft 477. A lever arm 276 which is keyed to rock shaft 269 and provided with a bifurcated outer end 277, movably engages the oppositely presented pins 278 carried by a vertical slide 279, said slide being provided with serrations 280 at its lower end which, in the positions of the parts shown in Figure 2^a, are disposed immediately over a forwardly-presented shelf 265^a on the reciprocatory tray 265. The operating connections for this device, are such that the shaft 477 rotates once during the time that the conveyor 260 travels the distance between two successive lugs 261, the result being that the rock-shaft 269 imparts a downward movement to slide 279 at each movement of the reciprocatory tray 265 away from the carton-conveyor. According to the present embodiment of my invention, there are six reciprocatory movements of tray 265 during the period of time consumed by one or the other of the charging trays 328 in passing from left to right (according to Figure 2^a) below the reciprocating slide 279. In consequence, each charging tray 328 is loaded with six poultices which are superimposed one upon another in the manner shown in Figures 10 and 12. For this purpose, each of said poultices is depressed by a downward movement of plunger 279 as the shelf 265^a is moved from under it.

As shown in Figure 11, a pair of laterally spaced side frames 281 are secured to the plate or table 18 by means of bolts 282, said side frames being provided with dove-tail guides 283 within which are reciprocably mounted slides 284, each of said slides being

provided with end lugs 285. Laterally projecting studs 286 carried by the end lugs 285, serve to journal rollers 287, said rollers being adapted to travel to and fro in slots 288 formed in the upper ends 289 of cam-operated levers 290. The lower ends of said levers 290 are provided with slotted ends 291 within which are adjustable studs 292 mounted in the outer end of laterally spaced links 293 which are pivotally mounted upon the oppositely presented ends of a bolt 294 carried by a bracket 295 on the bottom plate 1. Secured to the under side of table 18 are a pair of depending brackets 296 provided with bearings 297 at their lower ends. Reciprocably mounted in said bearings 297 are an upper cam rod 298 and a lower cam rod 299, the former having an enlarged end 300 (see Figure 16) provided with a longitudinal slot 301 within which is disposed a guide block 302 on the vertical cam-shaft 12. Journalled upon a depending stud 303 is a cam roller 304 which travels in a cam slot 305 in the upper face of a cam-disk 306. The cam-disk 306 is keyed to the cam-shaft 12 and slidably supports the cam rod 298 on its upper surface. Arranged below the cam 306 and keyed to the cam-shaft 12 is a similarly formed cam 307 (see Figure 2) provided with a cam groove 308 (shown in dotted lines in Figure 16). A cam roller 309 journalled upon a stud 310 travels in the cam groove 308, said stud 310 being carried by the widened end 311 of lower cam rod 299. By an inspection of Figure 16, it will be seen that the cam grooves 305 and 308 are adapted to impart substantially similar movements to cam rods 298 and 299, these movements, however, being displaced one with respect to the other in an amount corresponding to 180 degrees of cam travel. Bolted to the cam rods 298 and 299, are blocks 312 and 315 which carry studs 313 and 316 which pivot in levers 290. It will be understood from this description that the slides 284 have similar cycles of movement whereby they are alternately engaged in charging cartons presented by the carton-conveyor.

Referring now to Figures 10 and 11, bolted to each of the dove-tail slides 284, is a base plate 318 which carries axially spaced cylindrical housings 319 within which are arranged compression springs 320, a buffer disk 321 being interposed between one end of each spring and a ball 322 which is thereby yieldably retained in one or another of vertically spaced recesses 323 formed in the outer wall of a box-like housing 324 which is rigidly secured to a plunger bar 325. As shown in Figure 13 the plunger 325 is provided with a dove-tail slide 326 by means of which it is reciprocably mounted between vertical guide plates 318. Plunger 325 carries a stud 441 upon which is jour-

nalled a roller 442 arranged to be engaged by a fixed side bar 443 to positively limit the upward throw of plunger 325. Each of the plungers 325 carries at its upper end a forwardly-presented arm 327 which carries at its forward end a charging tray 328, the charging trays being offset from their respective plungers and adapted to move into and out of a carton presented in position to be charged by the carton-conveyor. For this purpose, suitable means are provided to adapt said charging trays to pass one under the other on their carton-charging movements. The poultices which may have been severed from a continuous stock as shown and described in my above-identified U. S. Patent No. 1,605,560 are made of a length which is slightly greater than the inside width of the loading trays 328 so that when said poultices are forced into said loading trays, they become firmly lodged as indicated in Figure 12. The lower end of each plunger 325 carries a stud 329 upon which is journaled a cam roller 330, said cam roller being adapted near the end of its movement toward the right according to Figure 2^a to be brought into engagement with an inclined cam surface 331 whereby the charging tray is depressed from the position shown in Figure 10, the oppositely arranged balls 322 being removed to the upper recesses or sockets 323. In the depressed position of one charging tray, a free passageway is left open for the withdrawal of the other charging tray from the carton. As shown in Figure 2^a, the forward movement of the lowered tray, causes its cam roller 330 to travel over a cam surface 332 in such a way as to again elevate the plunger 325 and bring the tray into position to enter the carton as shown in Figure 10.

Mechanism for transferring poultices from charging tray to cartons.

As shown in Figure 11, oppositely arranged bracket arms 333 are provided with terminal bearings 334 within which is oscillatably mounted a rock-shaft 335. Keyed to said rock-shaft is the hub portion 336 of a stop-arm 337 provided at its lower end with a transverse bar 338 which approximately covers the cross-sectional area of each of the charging trays 328. Keyed to the outer ends of the rock-shaft 335 are disks 339 provided with peripheral recesses 340 into which balls 341 are adapted to seat for retaining the parts in adjusted positions. Each of said balls is mounted in a cylindrical chamber within a housing 342, a buffer disk 343 being interposed between said ball and a compression spring 344 which exerts a tendency to retain said ball in either of the recesses in which it may be disposed. Keyed to the rock-shaft 335 are laterally spaced arms 345 to which are pivotally connected the inner

ends of connection rods 346, the other end of each of said rods being pivotally connected to a lever arm 347 (see Figure 2^a) which is oscillatably mounted upon a stud 348 carried by a bracket arm 349 which projects upwardly from either side frame. Adjustably mounted on each of the connection rods 346 are spaced stops 350 which are adapted to be engaged by an offset projection 351 carried by one or the other of the horizontal arms 327 at the upper end of plunger 325. It will be understood from this description that at the end of the forward movement of a charging tray 328, the projection 351 carried thereby will engage 75 the forward stops 350 and draw the stop-arm 337 into position to bar the removal of poultices from the carton during the withdrawal of said charging tray. At the end of its return movement, the projection 351 will engage the outer stop 350 and thus swing the stop-arm 337 away from the open end of the carton, the disk 339 being at the same time moved in a counter-clock-wise direction until the ball 341 enters into the lower recess 340. Journaled within the side frames is an oscillatory shaft 354 which carries an angular circular-retaining finger 352, said finger being adapted to be swung about the axis of shaft 354 into and out of engagement with the circular in the carton for retaining it in position within a carton during the charging operation. About the shaft 354 is a coil spring 353 which exerts a tendency to hold the bent finger 352 in raised position. It will be understood from this description, however, that as either of the charging trays 328 moves toward the left according to Figure 10, it will slide over said finger 352 and thus depress it into circular-engaging position as shown in this figure. Afterwards when the stop-arm 337 has been withdrawn from the carton and the tray 328 has moved toward the right, the finger 352 is released to swing upwardly 100 and away from said carton which is thus left free to be moved by the carton-conveyor into position to have the flaps at the open end folded into carton-closing position.

I claim:—

1. In a machine of the character described, the combination of a reciprocably-mounted circular-conveying slide arranged and adapted to enter an open end of a carton presented in suitable position to be charged thereby, a circular-propelling slide reciprocably-mounted on the first-mentioned slide, means for reciprocating the first-mentioned slide, and means for reciprocating the second-mentioned slide, the means for reciprocating the second-mentioned slide being adapted to delay the retraction of the second-mentioned slide until after the first-mentioned slide has been withdrawn from said carton. 115

2. In a machine of the character described, the combination with a carton-conveyor, of a reciprocably-mounted circular-conveying slide provided with a reduced forward end adapted to enter the open end of a carton presented by said carton-conveyor, a circular-propelling slide provided with circular engaging projections, said conveying slide being provided with cut-away portions in its reduced forward end to accommodate said projections on the propelling slide, means for reciprocating the first-mentioned slide, and means for reciprocating the second-mentioned slide, the last said means being adapted to delay the retraction of the second-mentioned slide until after the first-mentioned slide has been withdrawn from said carton.

3. In a machine of the character described, the combination with a carton-conveyor, of a reciprocable circular-conveying slide provided with a box-like vestibule at its forward end, said vestibule being contracted at its front end to form a reduced discharge outlet and to adapt it to enter the open end of a carton presented by said carton-conveyor, a reciprocable circular-propelling slide provided in front with circular-engaging projections, the contracted forward end of said box-like vestibule being provided with slots to accommodate said projections on the conveying slide, means for reciprocating the first-mentioned slide, and means for reciprocating the second-mentioned slide at relatively greater speed than the first.

4. In a machine of the character described, the combination with a carton-conveyor, of a reciprocably-mounted circular-conveying slide arranged and adapted to enter an open end of a carton presented by said carton-conveyor, a circular-propelling slide reciprocably mounted on the first-mentioned slide, means for reciprocating the first-mentioned slide, means for reciprocating the second-mentioned slide at relatively greater speed than the first, the means for reciprocating the second-mentioned slide being adapted to delay the retraction of the second-mentioned slide until after the first-mentioned slide has been withdrawn from said carton.

5. In a machine of the character described, the combination with means for presenting an open carton in position to be charged with articles, of a circular-conveying slide, a circular-propelling slide reciprocable relatively to the first-mentioned slide, a rack carried by the second-mentioned slide, a fixed rack, a cycloidal gear intermeshing between said racks for reciprocating the second-mentioned slide, and means for moving said cycloidal gear back and forth along the fixed rack.

6. In a machine of the character de-

scribed, the combination with means for presenting an open carton in position to be charged with articles, of a circular-conveying slide provided with a longitudinal slot in the bottom, a circular-propelling slide, a downwardly-presented rack carried by the second-mentioned slide, a fixed upwardly-presented rack, a cycloidal gear operating thru said slot and intermeshing between said racks for reciprocating the second-mentioned slide, and means for moving said cycloidal gear back and forth along the fixed rack.

7. In a machine of the character described, the combination with means for presenting an open carton in position to be charged with articles, of a circular-conveying slide, a circular-propelling slide reciprocable on the first-mentioned slide, said first-mentioned slide being adapted in retracted position to receive a circular in front of the forward end of the second-mentioned slide, a rack carried by the second-mentioned slide, a fixed rack, and a cycloidal gear traveling over said fixed rack and meshing with the rack carried by the second-mentioned slide.

8. In a machine of the character described, the combination with a carton-conveyor, of a circular-conveying slide provided with a box-like vestibule at its forward end, a circular-propelling slide reciprocable on the first-mentioned slide and having its forward end spaced from the rear end of said vestibule in the retracted positions of both slides, and means for reciprocating said slides.

9. In a machine of the character described, the combination with means for presenting an open carton to be charged with articles, of a circular-conveying slide provided with a box-like vestibule at its forward end, opposite walls of said vestibule being deflected inwardly to form a contracted discharge opening whereby the introduction of the circular into said carton is facilitated, said slide being provided with a longitudinal slot in the bottom thereof, a circular-propelling slide reciprocable on the first-mentioned slide, a downwardly-presented rack carried by the second-mentioned slide, a fixed upwardly presented rack, a cycloidal gear intermeshing between said racks for reciprocating the second-mentioned slide, and means for moving said cycloidal gear back and forth along the fixed rack.

10. In a packaging machine, the combination with a carton-conveyor, of circular-insert mechanism cooperatively arranged with respect to said conveyor, mechanism for charging a carton carried by said conveyor, and means cooperating with said charging mechanism for retaining a circular in position within the carton during the charging operation.

11. In a packaging machine, the combina-

tion with a carton-conveyor, of circular-insert mechanism cooperatively arranged with respect to said conveyor, means for charging articles into a carton carried by said conveyor, an article-carrier movable into an out of position to have articles discharged therefrom into said carton, a blade movable by said carrier into engagement with a circular within the carton, and means for moving said blade out of the path of said conveyor upon the removal of said article-carrier away from said conveyor.

12. In a packaging machine, the combination with a carton-conveyor, of means for inserting a circular into a carton carried by said conveyor, mechanism cooperatively arranged with respect to said conveyor for charging articles into said carton, a circular-retaining blade movable into and out of the path of a carton carried by said conveyor, and means tending to hold said blade out of the path of said carton, said charging mechanism including an article carrier movable towards and away from said conveyor and adapted to move said blade into engagement with said circular.

13. In a packaging machine, the combination with a carton-conveyor, of circular-insert mechanism cooperatively arranged with respect to said conveyor, mechanism for charging a carton carried by said conveyor, a blade oscillatable into and out of engagement with said circular within the carton, and means yieldably holding said blade out of the path of said conveyor, said charging mechanism including an article carrier movable towards and away from said conveyor and adapted to engage said blade for moving the latter into engagement with said circular.

14. In a packaging machine, the combination with a carton-conveyor, of an article-conveying tray movable towards and away from said carton-conveyor, means for raising and lowering said tray during its movements towards and away from said conveyor, said tray being adapted to enter a carton in charging position, means for charging said tray and means movable into and out of position to sweep the articles from said tray as said tray moves out of said carton.

15. In a packaging machine, the combination with a carton-conveyor, of a slide reciprocable towards and away from said carton-conveyor, a vertical slide carried by said horizontal slide, means for retaining said vertical slide in raised or lowered position, a cam-roller journalled on said vertical slide, means for raising and lowering said vertical slide, a tray carried by said vertical slide, said tray being adapted to enter the carton in charging position, means for charging said tray at a distance from charging position, and means movable into and out of position to sweep the articles from said tray as it moves away from said carton-conveyor.

16. In a packaging machine, the combination with a carton-conveyor, of laterally-spaced horizontal slides reciprocable with respect to each other and towards and away from said carton-conveyor, a vertical slide carried by each horizontal slide, means for retaining said vertical slides in raised or lowered position, means for raising each vertical slide during its travel in one direction and for lowering said vertical slide during its travel in the opposite direction, and a support for articles presented inwardly from each vertical slide.

17. In a packaging machine, the combination with a conveyor for moving a carton into and out of position to be charged, of laterally-spaced horizontal slides reciprocable alternately with respect to each other and towards and away from said carton in charging position, a vertical slide carried by each horizontal slide, yieldable means for retaining said vertical slide in raised or lowered position on its horizontal slide, a cam-roller journalled on said vertical slide, a cam-track arranged to engage said cam-roller during the travel of each horizontal slide in one direction for lowering said vertical slide, a cam-track arranged to engage the cam-roller for raising said vertical slide during the travel of said horizontal slide in the opposite direction, and a tray presented inwardly from each vertical slide.

18. In a packaging machine, the combination with a conveyor for moving a carton into and out of position to be charged, of laterally-spaced article-carriers reciprocable horizontally and vertically with respect to each other, means for charging said article-carriers during their movements away from charging position, and means movable into and out of position to sweep the articles from said article-carriers as they are moved away from said conveyor.

19. In a packaging machine, the combination with a conveyor for moving a carton into and out of position to be charged, of a slide reciprocable towards and away from said carton in charging position, a vertically-reciprocable slide carried by said horizontal slide, a cam-roller journalled on said vertical slide, a cam-track arranged to engage said cam-roller during the travel of the first-mentioned slide in one direction for lowering said vertical slide, a cam-track arranged to engage the cam-roller for raising said vertical slide during the travel of said first-mentioned slide in the opposite direction, a tray carried by said vertical slide, said trays being adapted to enter the carton in charging position, means for charging said tray during its movement away from charging position, and means movable into and out of position to sweep the articles from said tray as it moves from said carton.

20. In a packaging machine, the combination with a conveyor for moving a carton into and out of position to be charged, of laterally-spaced horizontal slides reciprocable alternately with respect to each other and towards and away from said carton in charging position, a vertical slide carried by each horizontal slide, yieldable means for retaining said vertical slide in raised or lowered position on its horizontal slide, a cam-roller journalled on said vertical slide, a cam-track arranged to engage said cam-roller during the travel of each horizontal slide in one direction for lowering said vertical slide, a cam-track arranged to engage the cam-roller for raising said vertical slide during the travel of said horizontal slide in the opposite direction, a tray presented inwardly from each vertical slide, said trays being adapted to enter the carton in charging position, means for charging said trays during their movements away from charging position, and means movable into and out of position to sweep the articles from said trays as said trays are retracted from said carton.

21. In a machine of the character described, the combination with a conveyor for moving a carton into and out of position to be charged, of a loading tray movable into and out of a carton in charging position, a rock-shaft operated by the movement of said loading tray, an arm carried by said rock-shaft and movable thereby into and out of position across the open end of said carton in charging position to sweep the articles from said tray as said tray is withdrawn from the carton, a detent disk keyed to said rock-shaft, and a yieldable detent yieldably engaging said detent disk.

22. In a machine of the character described, the combination with a conveyor for moving a carton into and out of position to be charged, of a loading tray movable into and out of a carton in charging position, a 45 rock-shaft, an arm keyed thereto, said arm being provided on its outer end with a cross-bar movable by said arm into and out of position across the open end of said carton in charging position to sweep the articles 50 from said tray as said tray is withdrawn from the carton, a lever arm keyed to said rock-shaft, a stop-bar connected to said lever-arm, and spaced stops mounted on said stop-bar, said stops being arranged to be 55 engaged by said loading tray during its movements toward and away from charging position.

23. In a machine of the character described, the combination with a conveyor for moving a carton into and out of position to be charged, of a loading tray movable into and out of a carton in charging position, a rock-shaft, an arm keyed thereto, said arm being provided on its outer end with a cross-bar movable by said arm into and out of position across the open end of said carton in charging position to sweep the articles 60 from said tray as said tray is withdrawn from the carton, a detent disk keyed to said rock-shaft, a yieldable detent yieldably engaging said detent disk, a lever-arm keyed to said rock-shaft, a stop-bar connected to 65 said lever-arm, and spaced stops mounted on said stop-bar, said stops being arranged to 70 be engaged by said loading tray during its movements toward and away from charging position.

ROBERT H. PLASS.
